UNITED STATES PATENT OFFICE.

ARTHUR L. STANFORD, OF CHICAGO, ILLINOIS.

TRACK-DRILL.

1,117,610.

Specification of Letters Patent. Patented Nov. 17, 1914.

Application filed May 8, 1914. Serial No. 837,316.

To all whom it may concern:

Be it known that I, ARTHUR L. STANFORD, a citizen of the United States, residing at Chicago, in the county of Cook and State 5 of Illinois, have invented certain new and useful Improvements in Track-Drills, of which the following is a specification.

The present invention relates to a drill more particularly adapted and intended for 10 use in connection with drilling holes through the webs of railroad rails, etc., for the purpose of repairs, etc.

The objects of the present invention are to provide a driving and driven member for 15 the drill mechanism and to supply an endless member for transmitting power from the driving to the driven member and to provide a casing or inclosure for the endless member.

20 A further object of the invention is to provide an upright frame and a horizontal frame which latter frame embodies members for engaging the rail.

25 A further object is to mount the drilling mechanism in the upright frame and to provide a support for the rear end of the drilling mechanism in the nature of a universal joint, and to provide a support for the forward end in the form of a swinging cradle.

30 A further object of the invention is to provide a quick and easy means for removing the drill from the track in case of an approaching train or otherwise.

35 A further object of the invention is to provide a means for feeding the drilling tool forward, which means shall be in the nature of a friction brake, and under the entire control of the operator.

40 A further object is to provide an automatic means for feeding the drilling tool forward and to further provide means for throwing the automatic feeding means into and out of operative condition.

45 The invention further consists in the features of construction and combinations of parts hereinafter described and claimed.

50 In the drawings: Figure 1 is a front view of the device of the present invention in operative position; Fig. 2 is a section showing the upright frame and the manner whereby it incloses or houses the endless member; Fig. 3 is a side view partly in sec-

tion of the device of the present invention; Fig. 4 is an enlarged sectional view of the drilling mechanism; Fig. 5 is a plan view of the assembled device with one of the operating handles broken away; Fig. 6 is a detail of the manually operated drill feed mechanism; and Fig. 7 is a detail of the gear mechanism for effecting the automatic feed. 55

Referring now to the drawings, and particularly to Fig. 1, the device as shown, comprises an upright frame 8 and a horizontal frame 9, this latter being better shown perhaps in Figs. 3 and 5. The frame 8 consists of outer tubular sections 10 joined by a web 11 and mounted in this frame is a sprocket 12 which may be termed a driving member, and this sprocket is actuated by means of crank arms 13 to which are connected suitable handles 14, the frame, as will be seen from the drawings, is suitably cut away to permit assembling of the sprocket. As shown in Fig. 1, the bearing for this sprocket is adjustable in order to 60 allow it to accommodate itself to take up any slack that may occur in the endless member. A sprocket 15 is located in the lower portion of the frame 8 and this sprocket may be termed the driven member, 65 and for the purpose of transmitting power from the driving member to the driven member I employ in the form illustrated a sprocket chain 16; it will be seen that the frame is suitably cut away to permit assembling of the sprocket. The sprocket chain, 70 as shown in Fig. 2, travels within the tubular portions 10 of the frame 8, and the tubular portion forms in effect a housing or closure for this chain whereby the danger 75 of its becoming clogged or choked by reason of dust or dirt is eliminated, thus insuring a free and easy operation of the drill. 80

What may be termed the drill mechanism proper consists of a spindle 17 and a stem 18, the spindle is formed with a chuck portion 17^a arranged to receive a suitable form of drill member 19. The spindle is formed with an interior bore 20 which is threaded to provide an interior threaded surface 21. 90 The stem 18 is enlarged at its forward end to provide a head 22 which is exteriorly threaded to mesh with the threads of the threaded surface 21. 100

The stem 18 terminates at its rear end in a ball 23, which ball is adapted to seat within the concavity 24 of the socket 25 which is pivoted at 26 to the rear end of the horizontal frame 9. The ball 23 forms the male member, and the socket 24 the female member, of a ball and socket joint. As will be readily understood from the drawings, this provides a ball and socket or universal connection between the drill mechanism and horizontal frame whereby the upright frame 8, together with the drill mechanism, may have any relative movement desired with respect to the horizontal frame, thus making the positioning of the drill a simple and easy matter.

The socket 25 is formed with a rearwardly projecting lug or lip 27 and a bar or key 28 is provided which, as shown in Figs. 3 and 5, is adapted to be inserted between the lower face of this lip and the upper edge of the rearward portion of the frame 9 and when so inserted securely locks the socket 25 against rearward movement and thus renders the socket a backing or resistance piece for the drill mechanism. When, however, it is desired to remove the drill the operation is quick and simple, and simply consists in driving or otherwise forcing the key or bar 28 from its position beneath the lug 27 whereupon the socket is free to swing upon its pivot 26, and the upright frame 8, together with the drill mechanism, can be tipped up or down as desired, and together with the frame 9, removed from position on the track. The frame 9 embodies companion forwardly extending hooks 29 which, as shown in Figs. 3 and 5, are adapted to hook over the rail and rigidly hold the drill in place. In these drilling operations it is highly desirable, and in fact essential, in a practical drill to provide means for feeding the drill tool forward. It is sometimes more advantageous to have such forward feed of a manual nature and under the direct control of the operator, so he may stop or start such forward feed as he desires, and at times it is preferable to have the forward feed automatic in its nature so that the operator need not be concerned with actuating the mechanism to effect such forward feed. I have therefore provided in the present construction both forms of mechanism, namely, an automatic feed and a manually controlled feed.

Referring first to the manual feed, as illustrated, it consists of a collar 30, splined or otherwise secured to the stem 18, so that said collar always rotates in unison with the stem and at the same time the stem is permitted a longitudinally sliding movement through the collar. This collar in the form illustrated is provided with an inverted U-shaped outer or acting face 31. I provide

companion members 32 each of which is 65 similar in construction, and these members are hinged together as at 33, each member embodying a semi-cylindrical portion 34 which has an inner face 35 configured to conform with the face 31 and, each member also 70 comprises a forwardly extending portion 36, which forwardly extending portions terminate in foot pieces 37 as will be observed from Fig. 6. The portions 36 are normally spaced away from one another and the forwardly extending portion of one of these sections normally rests against the upper surface of the tie. The above described mechanism constitutes in effect a band brake mechanism. It is obvious that as the operator 80 presses his foot against the uppermost of the portions 37 the tendency will be to bring the members 32 together, thus placing a pressure upon the faces 31 of the ring 30 and creating friction between the members 85 32 and said ring. As previously stated, this ring is keyed to the stem 18 and thus the friction produced as described, will tend to retard the rotary movement of the stem 18. The effect will be to cause the spindle 20 together with the drilling tool to advance in a forward direction. This, it is thought, will be clearly understood from the drawing, where as will be seen the stem cannot move rearwardly because of the engagement with the 95 socket 25. Therefore, the retarding movement of the stem will result in the threads of the head of the stem and of the chamber in the chuck coöperating to force the chuck and drill mechanism in a forward direction, 100 the speed of advancement of the drill member will be determined by the size of the threads, a fine thread making a slow advancement, and a coarse thread a fast advancement.

The foregoing described mechanism is, as stated, a manual mechanism for feeding the drill tool forward and is absolutely and entirely under the control of the operator. The formation of the spindle 17 is perhaps 110 better illustrated in Fig. 4 and as there seen consists of the usual split drill chuck 38 and which emerges into a sleeve-like portion 39. This sleeve-like portion has a threaded surface 40 upon which is mounted the driven 115 sprocket 15 and this connection between the spindle and sprocket rotates the sprocket in conformity with the actuation of the sprocket. A shoulder 41 is formed against which the sprocket abuts, thus locking the 120 same in place, since the tendency of the sprocket is to crowd against the shoulder when rotated by reason of the pitch of the threads.

The spindle at its rear end has gear teeth 125 42 which in the construction shown are cut in the body of the spindle, and these teeth mesh with the teeth of a gear 43 loosely

mounted upon a stub shaft 44, and splined upon the shaft is a gear 45. The end of the stub shaft is threaded at one end as at 46 and an interiorly threaded collar 47 engages with said threaded end which collar has joined thereto a hand wheel 48. The stub shaft 44 terminates at its other end in a nut or head 49. It is obvious that as the hand wheel is turned the tendency will be 10 to crowd the gears 43 and 45 together so that they rotate in unison, but upon loosening the hand wheel the gear 45 will not be rotated in unison with the gear 43 but the latter gear will simply turn idle upon the 15 stub shaft. This forms a means for throwing the automatic feed into and out of operation.

A gear 49 is splined to the stem 18 whereby it rotates in unison with said stem, but 20 is capable of having a longitudinal sliding movement with respect to the stem and there are a greater number of teeth in the gear 49 than in the gears 45, 43, or 42. This gear mechanism constitutes the automatic 25 means for causing the forward advancement of the chuck, and its operation is as follows: Assuming the gears 43 and 45 are brought together by manipulating the hand wheel 48, so as to rotate in unison, and assuming each of the gears 42 and 43 has twelve teeth, the gear 45 eleven teeth, and the gear 49 thirteen teeth. The effect will be to have the gear 49 rotate slower than the gears 42 and 43, and this gear 49 being 35 keyed to the stem 18 will retard the rotative movement of the stem, effecting the forward movement of the spindle as heretofore explained. Of course, the spindle in its forward movement will carry forward 40 the frame 8 together the mechanism joined thereto which will include the gears 43, 45, and 49, but owing to the construction all of the above mentioned mechanisms they are capable of a sliding movement with respect 45 to the stem 18, and can move forward, as desired.

From the foregoing, it will be observed that both in the manually operated forward feed drill as well as in the automatic feed 50 the said feed is produced by retarding the rotative movement of the stem 18. All portions of the drill are efficiently housed, the gear mechanism being inclosed by a housing 58 formed with the frame 8, one side of said housing being open and a cap plate 59 being provided for closing this open end.

As will be observed from the drawings, the frame 9 is of one piece construction, and is contracted at its rear end 52 to provide a 55 mounting for the pivoted socket member 25. In order to provide a guide for the forward end of the tool during the initial entrance, I arrange a flexible cradle 53 adjacent the forward end of the chuck, which cradle con-

sists of members in the form of rods 54, 65 which are hooked together at their abutting ends and are threaded at their outer ends. These threaded portions, in turn, are entered through lugs 55 on the bars of the frame 9 and by manipulating suitable 70 thumb nuts on the ends of the rods, the cradle can be raised or lowered. It will be observed that the cradle is flexible and that the drill mechanism, as a whole, is capable of a movement in any direction by reason of 75 the universal joint heretofore described. Therefore the tool is not held rigid so that it must under all circumstances follow a given line, but is free to move in any direction that may be most expedient during the 80 drilling operation thereby eliminating any danger of the drill becoming broken by jamming or wedging.

I claim:

1. In a track drill, the combination of 85 drill mechanism, means operatively connected for actuating the same, a horizontally disposed frame embodying members arranged to engage the rail, and a universal joint connection between the drill members 90 and horizontal frame, substantially as described.

2. In a track drill, the combination of 95 drill mechanism, means operatively connected for actuating the same, a horizontally extending frame embodying members arranged to engage the rail, a connection between the frame and drill mechanism consisting of a ball on the rear end of the drill mechanism and a socket on said frame 100 arranged to receive the ball, substantially as described.

3. In a track drill, the combination of 105 drill mechanism, means operatively connected for actuating the same, a universal joint for supporting the rear end of the drill mechanism, and a flexible cradle for supporting the forward end of the drill mechanism, substantially as described.

4. In a track drill, the combination of 110 drill mechanism, means operatively connected for actuating the same, a horizontally extending frame embodying members arranged to engage the rail, a socket member on the rear of said frame, a ball on the rear 115 of said drill mechanism seating in said socket, a flexible cradle joined to said horizontal frame and arranged to support the forward end of the drill mechanism, and means for raising and lowering said cradle, 120 substantially as described.

5. In a track drill, the combination of 125 drill mechanism, means operatively connected for actuating the same, a horizontal frame embodying members arranged to engage the rail, a socket pivotally connected to the rear of said horizontal frame, a member on the rear of the drill mechanism seat-

- ing in said socket and forming a universal joint between the drill mechanism and frame, and means for locking said socket in upright position, substantially as described.
6. In a track drill, the combination of drill mechanism, means operatively connected for actuating the same, a horizontal frame embodying members arranged to engage the rail, said frame being contracted at its rear portion, a socket pivotally mounted in said contracted portion, a member on the drill mechanism arranged to seat in said socket and means for maintaining the socket in upright position, substantially as described.
7. In a track drill, the combination of drill mechanism, means operatively connected for actuating the same, a horizontal frame embodying portions arranged to engage the rail, and said frame being contracted at its rear portion, a socket pivotally mounted in said contracted portion, a lip extending from said socket, a key arranged to pass beneath the lip and lie between the lip and the top of said frame to maintain the socket in upright position, and a member on the drill mechanism to engage with said socket and form a universal joint, substantially as described.
8. In a track drill, the combination of drill mechanism, means operatively connected for actuating the same, a horizontal frame embodying members arranged to engage the rail, a socket member pivotally secured at the rear of the frame, a lip extending from said socket, a locking member arranged to lie between the lip and the top of the frame to maintain the socket in upright position, a member on the rear end of the drill mechanism arranged to engage with said socket and produce a universal joint and a flexible cradle at the forward end of said frame for supporting the forward end of the drill mechanism, substantially as described.
9. In a track drill, the combination of drill mechanism including a spindle for carrying the drill tool and a stem, a threaded engagement between the spindle and stem, means operatively connected for rotating the spindle and stem and manually operated friction means operable separately from the spindle rotating means for retarding the rotation of the stem to advance the spindle and drill tool carried thereby, substantially as described.
10. In a track drill, the combination of drill mechanism including a spindle for carrying the drill tool and a stem, a threaded engagement between the spindle and stem, means operatively connected for rotating the stem and spindle and a band brake operable separately from the spindle rotating means for placing a friction upon the stem and retarding the movement thereof to advance the spindle, substantially as described.
11. In a track drill, the combination of drill mechanism including a spindle for carrying the drill tool and a stem, a threaded engagement between the spindle and stem, means for rotating the spindle and stem, a collar upon the stem, a member in the form of a band brake engaging said collar, a foot piece on the band brake for actuating the same, said brake when operated serving to retard the rotation of the stem and advance the spindle, substantially as described.
12. In a track drill, the combination of a spindle embodying a chuck portion for carrying a drill tool, said spindle having an interiorly threaded bore, a stem having threaded engagement with said interiorly threaded bore, means for rotating the spindle and stem, and means for automatically retarding the rotary movement of the stem to advance the spindle consisting of a gear connection between the spindle and stem imparting a reduced speed movement from the spindle to the stem, substantially as described.
13. In a track drill, the combination of drill mechanism including a spindle and a stem, a threaded engagement between the spindle and stem, means for rotating the spindle and stem, means for automatically retarding the rotary movement of the stem to advance the spindle consisting of a gear connection between the spindle and stem imparting a reduced speed movement from the spindle to the stem, and means for binding selected of said gears together and allowing them to move apart to position them respectively in and out of operative condition, substantially as described.
14. In a track drill, the combination of a spindle including a chuck for holding the tool, a stem, a threaded engagement between the stem and spindle, a gear on the spindle, a gear on the stem, a stub shaft, a gear on the stub shaft meshing with the spindle gear, a second gear on the stub shaft meshing with the stem gear, means for bringing said stub shaft gears into close relation causing them to rotate in unison, the ratio of the stem gear and the stub shaft gear meshing therewith being such as to reduce the speed of rotation of the stem from the speed of rotation of the spindle whereby the spindle is advanced, and means operatively connected for rotating the spindle and stem, substantially as described.
15. In a track drill, the combination of drill mechanism including a spindle having an interiorly threaded bore, said spindle embodying a chuck portion, a driven member for rotating the spindle, means on the

spindle for retaining the driven member thereon, a gear cut upon the surface of the spindle, a stem having a threaded engagement with the interior of the spindle, a gear 5 on the stem, and gears connecting the spindle gear with the stem gear to reduce the speed of rotation of the stem and cause a forward advance of the spindle, substantially as described.
